MOLD

Eric H. Zahn, Pound Ridge, N. Y., assignor to
Austenal Laboratories, Incorporated, New York,
N. Y., a corporation of New York

Application February 26, 1944, Serial No. 524,025

3 Claims. (Cl. 22—154)

1

This invention relates, generally, to molds, and has particular relation to improvements in hollow casting molds having one or more casting cavities the configuration and volumetric proportions of which are the same as a predetermined pattern.

In the production, for example, of wax or like patterns for use in making refractory molds in which articles are to be cast corresponding precisely to given specifications, maintenance of the accuracy of the mold in which the pattern is cast and avoidance of distortion of the pattern are of primary importance. As an illustration, in the production of turbine buckets such as disclosed in the copending application of Albert W. Merrick, Serial No. 422,421, filed December 10, 1941, now Patent 2,381,459 issued Aug. 7, 1945, the permissible tolerances are very close and require precision casting in the production of such buckets. Further, in the production of articles cast from metals or alloys characterized by extreme hardness and which are difficult to machine or grind, it is important that the cast article correspond precisely to specifications, from the practical production standpoint, and that necessity for grinding or machining the cast article be eliminated or held to a minimum. Accordingly, in precision casting, particularly of the character referred to, it is of the utmost importance that the mold be accurate at all times, which means that the sections of such mold must always be in accurate register during the casting operation, must not be distorted as a result of the pressure to which the mold sections are subjected while being held together during the casting operation, and must not be subjected to wear of a character to reduce their accuracy, and that the wax pattern or other article prepared in such a mold must be removed therefrom without distortion or impairment of its accurate reproduction of the mold cavity.

In my prior U. S. Patent No. 2,306,516, issued December 29, 1942, I disclose a method of making hollow casting molds of the general character above referred to. In accordance with the disclosure of this patent, the mold sections are formed of a comparatively soft alloy having a low melting point, specifically tin-bismuth alloy, which is cast about the pattern with an intervening parting medium in the form of a rubber membrane. The mold sections are provided with cooperating registering lugs and depressions, cast integral therewith, for assuring proper register of the mold sections in the assembled condition of the mold. Molds produced in accord-

2
ance with the above patent have proved to be highly efficient in casting patterns of wax or analogous materials under comparatively low pressures, but after continued use and resultant wear of the registering lugs and depressions, inaccuracies in the wax patterns produced may occur due to wear and inability to obtain accurate register of the mold parts. Also, if the comparatively soft mold sections are fitted with knock-out pins for releasing the wax pattern cast therein, these pins cause wear of the mold, increasing the inaccuracy thereof. I have found that, in using a mold constructed in accordance with my prior patent, the pressure required to hold the mold sections together during the casting operation may cause a slow flow of the metal of the mold sections, with a resulting alteration of the configuration of the mold cavity and the volumetric proportions of the patterns cast therein. This renders the patterns inaccurate and causes corresponding objectionable inaccuracy in the final casting produced in molds formed about the pattern.

25 My present invention is in the nature of an improvement over the mold of my prior patent, and is directed to avoiding the difficulties encountered in using such a mold under certain conditions. To that end, I provide a sectional mold having forming elements, produced in accordance with my prior teachings, for defining the mold cavity, these forming elements being effectively reenforced in such manner as to avoid distortion or inaccuracy thereof due to wear or pressure to which the mold sections are subjected during the operation of casting the pattern in the mold.

30 More specifically, each of the mold sections preferably comprises a forming element of relatively soft material mounted in a reinforcing member of relatively hard pressure resistant material, the reinforcing members being provided with the cooperating registering means for assuring proper register of the mold sections, and one of the mold sections at least being preferably provided with suitably disposed knock-out means operating through the forming element of that section, this knock-out means being mounted in and guided by the reinforcing member so as to avoid objectionable wear of the forming element. In the use of the mold, the pressure resistant reinforcing members are disposed in abutting relation, in the assembled condition of the mold, and serve to take the pressure to which the mold is subjected for holding the sections thereof tightly together in the operation

of casting the pattern, whereby the relatively soft forming elements of the mold sections are not subjected to such pressure and slow flow of the metal of the forming elements, with resultant inaccuracy of the mold cavity, is avoided. Further objects and advantages of my invention will appear from the detail description.

In the drawings:

Figure 1 is a plan view of the lower section of a mold embodying my invention;

Figure 2 is a section taken substantially on line 2-2 of Figure 1, through the upper and lower sections of a mold embodying my invention and through the knock-out pins guard plate;

Figure 3 is a sectional view taken substantially on line 3-3 of Figure 2; and

Figure 4 is a fragmentary sectional view taken substantially on line 4-4 of Figure 1.

I have shown my invention, by way of illustration, as embodied in a mold for producing patterns for articles of generally rectangular shape in plan and of concavo-convex cross section. This mold comprises an upper section 5 and a lower section 6. In forming section 6 of the mold I first provide a reinforcing member 7 of rectangular shape in plan and suitable thickness, conveniently formed of cast iron, or other suitable reinforcing material, having in its upper face a rectangular recess of uniform depth and of appropriate length and width suitable to the forming element of the mold to be received therein. The reinforcing member 7 is suitably finished by machining or otherwise, and has formed therein suitably disposed registering sockets 8. After the member 7 has been machined and finished and the registering sockets 8 have been applied thereto, a forming element 9 is cast in the recess in member 7, about a suitable pattern, in accordance with the method of my above identified prior patent. This element 9 is cast of a suitable alloy, such as the tin-bismuth alloy as referred to in said patent, which is relatively soft and has a low melting point, or of any other suitable material.

It is assumed, for purposes of illustration, that the pattern selected is such as to provide, in the exposed upper face of element 9, which may be referred to as its forming face, a plurality of recesses 10 of rectangular shape in plan and of arcuate cross section, these recesses being connected by pouring passages 11 of semi-circular cross section extending lengthwise of forming element 9, and relatively short passages 11a, also of substantially semi-circular cross section, extending transversely of forming element 9 and opening from passages 11 into the ends of the depressions 10. In casting the forming element 9 in the reinforcing member 7, the latter member is in inverted position, being provided through its then upper wall, which is its bottom wall in the normal position of member 7, with communicating sprue and gate openings. The gate opening may flare outward of member 7. The reinforcing member 7 is heated to a suitable temperature and the molten alloy is poured or injected into member 7 about the pattern, over which is disposed the rubber membrane, in the manner described in my above referred to patent. After the alloy has cooled and set to a proper extent, the member 7, with the forming element 9 cast and retained in the recess thereof, is removed from the pattern. The sprue and gate openings of the member 7 are filled with the alloy of member 9, providing sprue and gate elements 12 and 13 extending through the bot-

tom wall 14 of member 7, as shown. It will be noted that the areas of forming element 9 extending outward beyond the passages and depressions in the upper face thereof are flush with the upper face of the surrounding wall of the reinforcing member 7, for a purpose which will appear presently. The forming element 9 is further provided, at the sides of passages 11 and 11a, with narrow horizontal shoulders 15 and with beveled surfaces 16 extending upward and outward from the shoulders 15, to give the proper parting line for these passages, as will appear more fully later.

After the lower mold section 6 has been produced in the manner above described, the pattern is placed in this lower mold section, and the upper mold section is then produced, this upper section comprising an outer reinforcing member 17, conveniently formed of cast iron or other suitable reinforcing material. The reinforcing member 17 is machined and finished, and is provided with registering dowel pins 19, these pins and the sockets 8 being accurately located with respect to each other to assure accurate register of the two mold sections, in a known manner. The reinforcing member 17 is placed upon the lower mold section 6 in accurate register therewith, and over the pattern and the rubber diaphragm disposed thereover mounted in the lower mold section, after which the molten alloy is poured or injected into the recess in reinforcing member 17. The forming element 18 is thus cast and retained in reinforcing element 17 and is provided with sprue and gate elements 20 and 21, as shown.

After the lower mold section has been produced in the manner described, it is bored out from its lower face to provide a plurality of suitably disposed bores 23, from the upper end of each of which extends a concentric bore 24, of reduced diameter, opening into a coaxial bore 25 extending through forming member 9 at the mid-width of one of the passages 11 or 11a therein. The upper portion of bore 25 is counterbored to provide a downwardly tapering frusto-conical seat 25a in which seats the correspondingly shaped head 26 of a knock-out pin 27 slidably mounted through bore 24. Pin 27 extends downward beyond the bottom face of wall 14 of reinforcing member 7 and is urged downward, by a compression spring 28 disposed about pin 27 within bore 23 and confined between the wall at the upper end of this bore and a washer 29 mounted on pin 27 and restrained against downward movement therealong by the pin 30 secured through pin 27. Spring 28 normally holds head 26 of pin 27 seated against the seat 25a so as to form a fluid-tight closure therewith. In the use of the mold, the projecting ends of the pins 27 extend into recesses 31 in a removable steel guard plate 33 disposed at the bottom or back wall 14 of mold section 5.

Referring to Figures 2 and 3, the forming element 18 of the upper mold section is provided with rounded projections 34 overlying the depressions 10 in the forming element 9 and defining therewith mold cavities of concavo-convex cross section, the upper edges of which are in the plane of the upper face of the peripheral wall of reinforcing member 7 of the lower mold section. The upper mold section forming element 18 is further provided with lengthwise passages 35 and with relatively short transverse passages 36 complementary to passages 11 and 11a, respectively, 75 of forming element 9, and has downwardly ex-

tending ribs 38 in part defining passages 35 and 36 and disposed to seat on the shoulders 15 and 16 of the forming element 9, providing a parting line along the center of the circular passages defined by passages 11 and 11a, and 35 and 36.

The mold sections are provided with suitable sprue and gate openings for injecting wax or other suitable material into the mold cavities for producing the desired pattern. The sprue and gate openings may be provided in any suitable manner, though conveniently I provide a steel gate plate 40 which is secured to reinforcing member 7 of the lower mold section 6, in a suitable manner, as by means of a screw 41, member 7 being provided with a notch 42 in which the lower portion of plate 40 fits snugly, and reinforcing member 17 of the upper mold section 5 being provided with a notch for receiving snugly the upper portion of plate 40. This plate 40 and the two mold sections, with the sections held together in accurate register, are suitably bored to provide an outwardly flaring gate or socket 42 in plate 40, and a sprue opening 43 concentric with socket 42 and extending through the two mold sections and opening into passage 11 at the top thereof.

The two mold sections 5 and 6, when assembled in accurate register, define between them the mold cavities comprising the passages opening into the cavities corresponding to the articles to be produced. In using this mold, the sections are held together in a known manner under suitable pressure. The wax is injected into the mold cavity by means of an injector or gun having a nozzle which seats tightly in the gate or socket 42. The pressure under which the mold sections are held together depends largely upon the injection temperature and pressure of the wax, and in certain cases may be considerable. That pressure, if exerted upon the tin-bismuth alloy of the forming elements of the mold sections would, in the repeated use of the mold, result in slow flow or displacement of the metal of the mold sections, with resulting inaccuracy in the mold cavity, rendering the mold unfit for precision casting. It will be noted that in the assembled condition of the mold sections, these sections are in abutting relation, seating accurately one on the other, so that the pressure to which the mold sections are subjected for holding them together is taken by the outer cast iron reinforcing members thereof, these reinforcing members being relatively hard and pressure resistant and of relatively great mechanical strength, well able to withstand the pressures to which they are subjected. That relieves the forming elements 9 and 18 of the mold sections of objectionable pressure, such as would tend to cause displacement or slow flow of the metal thereof with resulting inaccuracy in the mold cavity.

After the wax pattern has been cast in the mold in the manner described, the mold is released from the holding means, upper section 5 of the mold is removed, and, after removal of the guard plate 33, the knock-out pins 27 are moved simultaneously upward through the lower mold section, by suitable means provided for that purpose, thus lifting the wax pattern from the lower mold section and permitting ready removal 70 of the pattern without risk of distorting or otherwise damaging it. The pattern thus produced is then used to produce a refractory mold, in a known manner, having a mold cavity conforming accurately to the wax pattern. This refractory

mold is then used for casting therein the desired article.

It will be noted that the mold shown and described herein is intended to provide a pattern for casting five articles corresponding to the mold cavities defined by the depressions or recesses 10 of forming element 9 and the corresponding projections 34 of the forming element 18. The articles are thus cast in a group and, as cast, are connected together by the elements corresponding to the passages defined by the semi-circular passages or depressions 11, 11a, and 35 and 36 of the mold sections, these passage elements being cut from the articles in a known manner.

15 The knock-out pins are mounted in and guided by the reinforcing member 7 of the lower mold section 6 so that no objectionable wear of the forming element 9 of this mold section is caused by operation of these knock-out pins. Likewise, the registering studs and sockets of the mold sections are carried by the reinforcing members thereof, which do not wear to any appreciable extent, so that no wear from the registering means is imposed upon the forming elements of the mold, avoiding inaccuracy from that cause.

20 In addition, by providing the reinforcing members for the mold sections, the amount of alloy or other material used in the forming elements of the mold sections is much less than would be the case if the mold section were formed in its entirety of the alloy, thus effecting a material saving in the alloy or other material used for the forming elements of the mold sections.

While I have shown a two section mold embodying my invention, by way of example, it will be understood that the mold may be formed of any suitable number of sections, as conditions may require. Likewise, the particular shape of the mold, as well as of the mold cavity, may be varied within wide limits and will depend upon the article to be produced and related factors, as will readily be understood by those skilled in this art. While I have referred to the forming elements of the mold sections as being formed of a tin-bismuth alloy, and the reinforcing members of the mold sections as being formed of cast iron, any other suitable materials may, within the broader aspects of my invention, be used. It will be understood that the details of my invention described and illustrated herein may be modified without departing from the spirit and scope of my invention, and I intend to include all such variations, as fall within the scope of the appended claims, in this application in which 55 the preferred form only of my invention has been disclosed.

I claim:

1. In a casting mold of the class described, in combination, a plurality of complementary mold sections each consisting of an outer hard and wear resistant reinforcing shell member and an inner lining of low fusing cast metal softer than said outer reinforcing member and fitting tightly within said outer wear resistant shell member, the face of at least one of said relatively soft linings which is opposed to the cooperating face of the other lining having a casting cavity of a shape for casting the desired object, said linings completely enclosing and defining the casting cavity throughout its entire extent so that none of the surfaces of said outer members is exposed to said cavity, registering ingate openings one in said lining and the other in at least one of said outer members through which the molten material to be cast is introduced.

cavity in said lining from outside said outer members with the mold sections assembled in casting relation, ejector means slidingly mounted in and guided by at least one of said outer members and operable through its softer lining into engagement with the object cast in said cavity to eject same from the casting cavity, said ejector means being normally constrained to a position projecting from the outer surface of the adjacent outer reinforcing member, and a removable guard plate fitting against the outer surface of said outer member in position covering said ejector means and having a recess for receiving said ejector means to guard said ejector means against actuation and permit application of the guard plate to said outer member without actuating said ejector means.

2. In a casting mold of the class described, in combination, a plurality of complementary mold sections each consisting of an outer hard and wear resistant reinforcing shell member and an inner lining of low fusing cast metal softer than said outer reinforcing member and fitting tightly within said outer wear resistant shell member, the face of at least one of said relatively soft linings which is opposed to the cooperating face of the other lining having a casting cavity of a shaft for casting the desired object, said linings completely enclosing and defining the casting cavity throughout its entire extent so that none of the surfaces of said outer members is exposed to said cavity, registering ingate openings one in said lining and the other in at least one of said outer members through which the molten material to be cast is introduced into the casting cavity in said lining from outside said outer members with the mold sections assembled in casting relation, ejector means slidingly mounted in and guided by at least one of said outer members and operable through its softer lining into engagement with the object cast in said cavity to eject same from the casting cavity, said ejector means being normally constrained to position projecting from the outer surface of the adjacent outer reinforcing member, and a removable guard plate fitting against the outer surface of said outer member in position covering said ejector means and having a recess for receiving said ejector means to guard said ejector means against actuation and permit application of the guard plate to said outer member without actuating said ejector means, said guard plate being disposed at the bottom of the mold to support the same and said ejector means being adapted to be actuated to ejecting position by placing the cooperating surface of the outer member of the mold upon a support with said guard plate removed.

3. In a casting mold of the class described, in combination, a plurality of complementary mold sections each consisting of an outer hard and wear resistant reinforcing shell member and an inner lining of low fusing cast metal softer than said outer reinforcing member and fitting tightly within said outer wear resistant shell member, the face of at least one of said relatively soft linings which is opposed to the cooperating face of the other lining having a casting cavity of a shape for casting the desired object, said linings completely enclosing and defining the casting cavity throughout its entire extent so that none of the surfaces of said outer members is exposed to said cavity, registering ingate openings one in said lining and the other in at least one of said outer members through which the molten material to be cast is introduced into the casting cavity in said lining from outside said outer members with the mold sections assembled in casting relation, ejector means slidingly mounted in and guided by at least one of said outer members and operable through its softer lining into engagement with the object cast in said cavity to eject same from the casting cavity, said ejector means being normally constrained to position projecting from the outer surface of the adjacent outer reinforcing member, a removable guard plate fitting against the outer surface of said outer member in position covering said ejector means and having a recess for receiving said ejector means to guard said ejector means against actuation and permit application of the guard plate to said outer member without actuating said ejector means, and spring means confined entirely within the adjacent outer reinforcing member of the mold and coacting with said ejector means normally to constrain said ejector means to non-ejecting position.
